JOHN WILCOX, OF THOMPSONVILLE, CONNECTICUT.

Letters Patent No. 63,126, dated March 19, 1867.

IMPROVEMENT IN VALVES.

The Schedule referred to in these Letters Patent and making part of the same.

TO ALL WHOM IT MAY CONCERN:

Be it known that I, JOHN WILCOX, of Thompsonville, in the county of Hartford, and State of Connecticut, have invented a new and improved Screw Valve; and I do hereby declare that the following is a full, clear, and exact description thereof, which will enable others skilled in the art to make and use the same, reference being had to the accompanying drawings, forming a part of this specification.

My invention consists in the construction and manner of securing the valve to its seat so as to operate it by a screw, whereby it is adapted to various purposes and overcome difficulties which have hitherto been experienced in opening and closing apertures for the admission or discharge of air, gas, steam, or liquids, as will be hereinafter described.

Figure 1 represents a vertical section of the valve and seat through the line $x x$ of fig. 2.

Figure 2 is a horizontal section of fig. 1, through the line $y y$.

Similar letters of reference indicate like parts.

A is the valve portion with the screw attached, and B is the seat. It is a section of a tube having an interior screw-thread and with exterior shallow grooves for the purpose of more conveniently attaching it to an elastic tube when desired. This interior screw-thread is double in its upper portion or in that portion in which the thread on the valve works. In order to make a stop for the valve after it is opened, as represented in fig. 1, one of the threads in the seat is cut out up to a point, a , and a stop-piece, b , is attached to the valve portion, which (as the valve is unscrewed) comes in contact with the point a , thus preventing the valve from being raised entirely out, and as seen in the drawing. The screw upon the valve fits into the remaining double thread left in the seat portion. The valve is formed by attaching a short section of a tube, c , to the valve piece properly by legs or studs, d , thus leaving intervals or spaces between them for the admission or discharge of air liquids, &c., and attaching their other ends to the cap-piece of the valve. These studs are plainly shown in fig. 2. The valve is made tight in its seat, either by making a ground metallic joint, or as seen in the drawing, by pressing the flange e (which is seen on the under side) on to some elastic packing d' , which lies in a recess in the seat. For this recess and device for keeping a valve tight in its seat, I have an application for a patent now pending. The valve is turned in and out in any convenient manner. In the one represented the outer edge of the valve-cap is "milled" for that purpose. This valve is particularly adapted to the elastic life-preserved, where the common pressure of the atmosphere is found to be all that is necessary, but for water basins and pipes, bottoms of boats, tanks, bathing tubs, and various other purposes, it will be found to be a very valuable improvement.

Having thus described my invention, what I claim as new, and desire to secure by Letters Patent, is—

A valve constructed, arranged, and operating substantially as herein shown and described.

I claim the stop arrangement $a b$ substantially as herein set forth, in combination with a screw-valve.

I claim the stop arrangement $a b$ substantially as herein set forth, in combination with a screw-valve.

The above specification of my invention signed by me this 21st day of November, 1866.

JOHN WILCOX.
